UNITED STATES PATENT OFFICE

WILLIAM A. FONKEN, OF SEATTLE, WASHINGTON

PEAR PEELING MACHINE

Application filed September 12, 1927. Serial No. 219,068.

This invention relates generally to the canner's art, and particularly to the preparation of pears for canning.

The main object of this invention is to provide a machine which will materially reduce the cost of removing the skin from pears and similar fruit by reducing the amount of labor and time consumed in the operation, as well as greatly reducing the amount of waste usually accompanying such operations.

The second object is to reduce the amount of oxidation and softening of the fruit usually caused by long exposure to the atmosphere by shortening the time of such operation.

The third object is to improve the quality of the output by making the individual pieces absolutely uniform as to shape and leaving the corners where the pears are halved sharp and well defined instead of rounded, as is the case where oxidation must be contended with.

The fourth object is to encourage the canning of pears by bringing the canning cost nearer to that of other canned fruits of a similar nature.

These, and other objects, will become more apparent from the specification following as illustrated in the accompanying drawings, in

which:

Figure 1 is an end elevation of the machine. Figure 2 is a vertical section through the machine taken along the line 2—2 in Figure 1. Figure 3 is a vertical section taken along the line 3—3 in Figure 2. Figure 4 is a plan view taken in partial section along the line 4—4 in Figure 2. Figure 5 is a perspective view of the suction cup carrier. Figure 6 is a perspective view of the bearing for the suction cup carrier. Figure 7 is a diagram of the suction piping and associated parts. Figure 8 is a perspective view of the control valve. Figure 9 is a perspective view of the bearing or seat for the control valve. Figure 10 is a horizontal section taken along the line 10—10 in Figure 1. Figure 11 is an enlarged view of the pear centering mechanism shown in plan. Figure 12 is a sectional view through the pear suction cup and knife.

Similar numbers of reference refer to similar parts throughout the several views.

Referring in detail to the drawing, the machine includes a pair of legs 15 across which is secured a base 16 on whose ends are mounted the end frames 17 which support the table 18. The machine is preferably mounted over a suitable conveyor 19 on which the peeled pears are carried away.

At each side of the base 16 is mounted a suction cup carrier bearing 20 which is made fast to the base 16 by the bolts 21. The face 22 of each bearing 20 is provided with an annular groove 23 having a radial connecting passageway 24 joining same with a short inner groove 25. An opening 26 from the passageway 24 extends through the bearing 20 and is connected with a suction pipe 27 which branches from the main suction pipe 28 which extends to both ends of the machine.

It may here be stated that the machine is in duplicate—that is the same operation is performed at its opposite ends, and the necessary parts are therefore in duplicate although they are described only once.

In the bearing 20 is also an opening 29 which is joined by the pipe 30 to parts which will be described later. In the bearing 20 journals the shaft 31 on which is splined the suction cup carriers 32. Each suction cup carrier is cylindrical in form and is provided with radial holes 33 in which are mounted the suction cups 34 having a flat pear-shaped perforated face 35 against which the pears are held. Each radial hole 33 has a connecting passageway 36 which terminates in an arcuate slot 37 which can register with the openings 29 in the bearing 20. An opening 38 is formed in the table 18 for the suction cups 34.

Between the suction cup carrier bearings and mounted on the base 16 are the standards 39 and 40 across the top of which is mounted the drive shaft 41 on which is secured a hand wheel 42, a belt pulley 43 and a pinion 44. In the standard 40 is keyed a valve bearing 45 having an opening 46 which connects with the pipe 30. An annular groove 47 is formed in the face 48 of the bearing 45 and has an

inwardly pointing branch 49 which terminates in a hole 50 extending through the bearing 45 and connecting with the pipe 51, which branches from the main suction pipe 28.

Against the face 48 of the bearing 45 bears the control valve 52 having a semi-circular groove 52^a formed in its lateral face which can register with the holes 46 and 50. The valve 52 is keyed on the shaft 53 which journals in the bearing 45 and the standard 39.

Each projecting end of the shaft 53 has mounted theron a curved knife 54 shaped like the half of a pear and coaxial with the major axis of the pear-shaped suction cup 34.

On the shaft 53 is also mounted the lock 55 of a Geneva stop member whose driven element 56 is keyed on the shaft 31. The roller 57 of the Geneva stop is mounted on the gear 58, which is keyed on the shaft 53.

In order to peel the pear 59 it is first necessary to properly place same on the suction face 35 and in an approximately correct position to avoid undue waste and also to secure perfect peeling. To accomplish this object an auxiliary shaft 60 is provided on which is mounted a curved lever 61 which is actuated by the roller 57. A stop screw 62 is provided for the lever 61, which lever is urged toward its stop by the spring 63. On the shaft 60 is also secured a lever 64 having a spring 65 connecting it to the end of the bell crank lever 66 on whose end 67 is mounted a pair of fingers 68 which are geared together and provided with a spring 69 which urge the finger tips toward a partially closed position, but only with sufficient power to enable same to be spread apart when the small end of a pear is inserted between same.

On the opposite side of the suction cup 34, and slidably mounted in the table 18, is a pear pusher plate 70 which is operated by a bell crank lever 71 which, in turn, is actuated by the link 72 on the lever 73 which is mounted on the shaft 60.

The operation of the machine is as follows: A pear 59 is placed on the face 35 and the fingers 68 are moved down in front of the small end of the pear while the pear pusher plate 70 is approaching the large end of the pear in a horizontal plane with the downward movement of the fingers 68 a little in advance of the horizontal movement of the plate 70. When the fingers 68 rest against the table 18 their further movement is prevented thereby, and any further movement of their operating lever 64 merely results in the stretching of the spring 65, during which time the plate 70 is pushing the small end of the pear 59 between the fingers 68 thereby centering same above the pear-shaped suction surface 35.

The uninformed person might be of the opinion that this would result in a wastage of fruit due to the different sizes of pears which naturally would be encountered. This

objection is overcome, as is now overcome in hand peeling, by first grading the fruit according to size and adjusting the knives or substituting different knives to correspond with the particular grade of pear being peeled.

Having been properly positioned upon the suction face 35 and the turret or suction cup carrier 32 being held stationary by the Geneva stop mechanism it now follows that air having been exhausted from the opening 26 and the groove 23 that the members 20 and 32 will be held to a seat and that air will be exhausted from the suction cup 34 causing the pear to be firmly held in its centered position. As the turret 32 now revolves the cup carrying the pear is carried in front of the knife 54, whose continuous rotation is timed to cause the knife 54 to move around the half pear and completely remove its skin.

It will be noted that while this operation is taking place that the half pear is also held against its seat on the face 35 by means of a suction, but that this suction is intermittent rather than continuous, as is the case in the first portion of the operation. This intermittent application of suction to the cup 34 is secured by the action of the valve 52 against the bearing 48, which members are also held to a seat by the annular groove 47 to which suction is continually applied, but, owing to the relation between the holes 46 and 50 in the member 45 to the groove 52^a, it can be seen that when the groove 52^a registers with both of the openings 46 and 50 that a suction will be applied to the cup 34 during that space of time only which corresponds with the time of the peeling operation. At this point the holes 46 and 50 are out of register with the groove 52^a and the turret 32 again moves and the pear is dropped upon the conveyor 19.

This operation can be better understood from Figure 7 wherein a continuous suction is provided from the pipe 28 and the branches 27 and 30, to the annular grooves 23 and 47.

It will be understood that this continuous suction is used for a double purpose, namely the holding of the particular parts to their seats and, in the case of the pear centering position, to hold the pear in position after being centered until this task is taken up by the intermittent suction imposed by the registering of the groove 52^a with both the holes 46 and 50 at the same time.

Attention is drawn to my co-pending application, Serial Number 162,278 in which the action of the suction cup is more fully described.

I claim:

1. A half-pear peeling machine having, in combination, a pear holder; a curved knife for removing the skin from a half-pear held on said holder; means movable with respect to the holder for positioning a half-pear on said holder; and means for rotating said

knife in a manner to peel said half-pears while held on said holder.

2. A pear peeling machine having, in combination, a suction plate for holding the flat side of a half pear and having the shape of the flat face of an axially split pear; a rotatable knife mounted coaxial with the major axis of said pear holder; means for centering a half-pears on said holder; and suction applying means whereby a half-pears can be held against said plate while said knife is moving around said pear for the purpose of peeling same.

3. A pear peeling machine having, in combination, a rotatable turret having a plurality of flat suction plates mounted on the periphery thereof; means for rotating said turret intermittently; positioning means adjacent to one of said suction plates; a paring knife alongside of the next adjacent suction plate; means for applying suction to a cup after a cut section of a pear has been positioned thereon while its skin is being removed therefrom by said knife; and means for releasing the suction from the cup holding the pear after the completion of the peeling operation.

4. A pear peeling machine consisting of a pair of bearings; a shaft journaling in said bearings; a pair of turrets on said shaft seated against the inner sides of said bearings; a plurality of suction cups mounted on each turret having flat perforated pear-shaped faces; means for centering a half-pears on one of said plates; a second shaft having an axis concentric with the major axis of a suction cup next adjacent to said positioning plate; a knife mounted on the end of said shaft adapted to remove the skin of a half-pears during the revolution of said second shaft; an intermittent drive between said first and second shafts; and suction means actuated by the rotation of said shafts whereby suction is applied to the under side of a half-pears after it is positioned on its holder and maintained until the peeling operation is completed.

5. A pear peeling machine having, in combination, a turret shaft; a plurality of turrets mounted thereon each of said turrets having a plurality of pear-shaped suction cups mounted on its periphery having a flat outer face perpendicular to the radius on which said plate is positioned; a drive shaft to which power can be supplied; an intermediate shaft between said drive and turret shafts; an intermittent drive between said intermediate shaft and said turret shaft; knives on said intermediate shaft registering with one of said turret positions of said suction plates in a manner that the rotation of said intermediate shaft will cause said knife to sweep across said plate while stationary; and suction-applying means whereby a half pear

can be held against said plate while its skin is being removed by a knife.

6. A pear peeling machine having, in combination, a turret having a plurality of suction cups mounted thereon and consisting of a body member having a plurality of lateral recesses formed therein communicating with said suction cups; a shaft for said turret; a bearing for said shaft having one face seated against said turret, said bearing having a suction recess formed therein adapted to hold said turret and bearing to a seat; and a separate hole in said turret whereby air can be extracted from a cup mounted on said turret.

7. A pear peeling machine having, in combination, a base; a pair of spaced bearings mounted on said base; a turret shaft mounted in said bearings; a turret mounted on said shaft; a plurality of suction cups mounted on the periphery of said turret, each of said cups having a flat pear-shaped outer face; a pair of standards mounted on said base between said bearings; a drive shaft and an intermediate shaft driven thereby mounted on said standards; an intermittent drive between said intermediate shaft and said turret shaft; a pear positioning means whereby half pears can be placed with their flat sides against said suction plates; and means for applying suction to each plate after a pear is positioned thereon and maintaining said suction until said pear is moved to its next position and its skin is removed therefrom.

8. In a fruit paring device, a holder having a flat face similar to the cut flat face of the fruit portion to be pared but slightly smaller, means for holding a cut fruit portion on the holder, means for correcting an inaccurate positioning of the fruit portion on the holder, and means for removing the skin of the fruit portion while so held.

9. In a pear paring device, a holder, a curved knife movable to pare the skin from a half pear supported by the holder, means for positioning the half pear on the holder, and means for holding the half pear with respect to the holder during the stroke of the knife and for ejecting the peeled half pear from the holder.

10. In a device of the character described, a rotatable member for receiving a plurality of axially split pear sections each with its cut face toward the axis of revolution, skin severing means, and means for holding the pear sections during the cutting operation and for later discharging the pared sections.

11. In a pear peeler, a rotatable member, a plurality of suction cups thereon each to receive an axially split pear half, peeling means in the path of the pear halves on the member, and suction and pressure means for successively exhausting the air from the suction cups during peeling and forcing air into the

suction cups after the peeling operation is completed.

12. The device of claim 11 in which each pear half is automatically positioned with respect to the peeling means just prior to the 5 exhausting of the air from the cup holding it.

13. The device of claim 11 in which the rotatable member is an intermittently rotated turret and the peeling means includes a 10 single piece knife which rotates about an axis centrally positioned with respect to a suction cup during its period of dwell.

14. The device of claim 10 in which the rotatable member has a plurality of equi-spaced pear half receiving portions each being 15 flat and having the outline of an axially split pear.

15. In a pear peeler, means for holding a plurality of axially split pear halves with the 20 skin of the pear sections entirely free, means for peeling the pear halves while so held, and means for discharging the peeled half pears.

16. The device of claim 15 in which the 25 pear half holding means and the discharging means are both pneumatic.

17. In a pear peeler, a turret, pneumatic means for temporarily securing axially split 30 pear sections on the turret, means for removing the skin from the pear sections while so held, and means for conveying the peeled pear halves from the turret.

18. The device of claim 17 in which inaccuracies in the relative position of pear sections and turret are corrected automatically 35 just prior to the peeling operation.

WILLIAM A. FONKEN.
